UNITED STATES PATENT OFFICE.

CHARLES L. STROBEL, OF PITTSBURG, PENNSYLVANIA.

BRIDGE TRUSS OR GIRDER.

SPECIFICATION forming part of Letters Patent No. 309,171, dated December 9, 1884.

Application filed February 11, 1884. (No model.)

To all whom it may concern.

Be it known that I, CHARLES L. STROBEL, a citizen of the United States, residing at Pittsburgh, county of Allegheny, State of Pennsylvania, have invented or discovered a new and useful Improvement in Bridge Trusses or Girders; and I do hereby declare the following to be a full, clear, concise, and exact description thereof, reference being had to the accompanying drawings, making a part of this specification, in which—like letters indicating like parts—

Figure 1 is a diagrammatic side view in elevation of a bridge, illustrating the combination of curved members as employed in my invention; Figs. 2 and 3, similar views of bridges embodying my invention, illustrating, respectively, different arrangements of chord members in the end spans; Fig. 4, a similar view illustrating the action of the chord members in maintaining the pier-posts in position; Fig. 5, a similar view illustrating a modification in the end spans; Fig. 6, a similar view showing single chord members in each span, and Fig. 7 a similar view showing the application of my invention in a bridge having both "deck" and "through" spans.

The object of my invention is to provide a truss or girder for bridges, the employment of which shall effect, among other advantages, those of enabling the erection of the bridge to be facilitated and economized, the strains sustained to be accurately determined and provided for, and those of temperature eliminated, a reduction in the cost of superstructure and masonry, simplicity of construction, and a light and graceful appearance.

To these ends my improvement, generally stated, consists in a truss for the intermediate span or spans of a bridge, in which are combined a catenary and arch member and a chord member or members connecting the pier-posts of the truss, and also in the combination, with one or more intermediate spans, as stated, of end spans continuous therewith, and having anchorages adapted to admit of expansion and contraction of the trusses due to changes of temperature.

The improvements claimed are hereinafter fully set forth.

In the practice of my invention I form the intermediate span or spans of a bridge having three or more spans or bays of lenticular trusses, 7 8 9 10, Figs. 1 to 3, each composed of two curved members, one of which is downwardly curved substantially as a catenary, and the other is an upwardly-curved arch. Said curved members are connected at their intersections 7, 8, 9, and 10, which constitute points of contraflexure, and are thence extended and connected to pier posts or supports 2 22 3 23 4 24, &c. The curved members of each span are connected together by any suitable system of struts and ties inserted in the ordinary manner in the spaces between them, and the pier-posts are connected one to the other and to the ends of the bridge by chord members, which are substantially straight, the connections being made either at the lower ends only of the pier-posts by chord members 12 13 14 15, or at both their lower and their upper ends by chord members 12 13 14 15 and 16 17 18 19. In the end spans of the bridge a semi-catenary is combined with an arch, said members connecting at points 6 11, located at their intersections nearest the pier-posts 2 22 and 4 24 of the adjacent intermediate spans, and at their opposite ends uniting in common points 1 5 at the extreme ends of the bridge. Where upper chord members are employed in the end spans, as in Figs. 2 and 3, they may either extend from the upper ends, 2 4, of the pier-posts to the end connections, 1 5, of the curved members, as shown in Fig. 2, or from the pier-posts to points 20 21 in the arch members, as shown in Fig. 3, the strains being thence transmitted through the arch members to the points 1 5.

The truss above described partakes, as will be seen, of the nature of a continuous girder, with points of contraflexure fixed in position.

The parts which are merely accessory, and not essential to the truss, are shown in the several figures in dotted lines. The deck or floor supports of the center span are thus indicated in Fig. 5, and in a construction similar to that shown in Fig. 7 it will be advisable to introduce vertical posts, as in the dotted lines, to support the chords at each panel-point, said posts also carrying the floor-beams. 100

In Figs. 2, 3, and 4 the non-essential members are wholly omitted, for greater clearness of illustration.

I have not herein illustrated or described the specific constructive details of the several members, as the same do not, *per se*, constitute part of my present invention, and are, further, familiar to those skilled in the art of bridge construction. It will, moreover, be obvious that it is not essential that the arch members should be of any prescribed regularity, nor that the downwardly-curved members should be necessarily in catenary form. Said members may be circular arcs, or may be parabolic, elliptic, or irregular, as deemed in particular cases most convenient or desirable, and will, in practice, be made up of straight lines between panel-points, the succession of said lines approximating to the form of curve desired. The strains in the catenary being tensile and those in the arch compressive, said members are to be constructed in the usual manner proper to receive and transmit strains of such character, the tension member being formed, preferably, of eye-bars, and the compression member of plates and angles. The action of the chord members in holding the pier-posts in position is exemplified in Fig. 5. The upper chord-line may be made a tension member, in which case the lower chord-line will be a compression member; or the character of the chord-lines may be reversed, the upper then being a compression and the lower a tension member.

Assuming the bridge to be composed of four spans, as indicated in Figs. 1, 2, and 3, and the points of contraflexure, 6 7 8 9 10 11, to be located at equal distances, measured horizontally, on each side of the supports or pier-posts, and that the lenticular trusses formed in each span by the before-described combination of catenary and arch members are of the same span length, (measured by projection on a horizontal line,) there will then, for equal loads, be such balance of forces that equilibrium would be maintained without the necessity of employing other or further truss members than those indicated. At the points 1 and 5 the thrust of the arch will be counteracted by the pull of the catenary, and there will be no strain in the direction of the line 1 5. The bridge will exert upon its supports at 1 22 23 24 5 vertical pressures only, and may, therefore, be placed upon rollers, so as to be free to expand and contract under the effects of temperature. No temperature strains, consequently, require to be provided for.

In order to render each span capable of carrying unequal loads, or loads covering a portion only of the span, as is requisite in bridges, especially those of railways, it is necessary to provide the strut and tie bracing between the curved members and the chords connecting the ends of the pier-posts with each other and with the ends of the bridge, as before specified. The chord members prevent the pier-

posts from canting over longitudinally in consequence of the application of a heavier load to one span than to others, and the bracing 73 between the curved members forms, in connection therewith, rigid trusses between points of contraflexure.

Under the conditions assumed as to the position of the points of contraflexure relatively 75 to each other and to the pier-supports the chords 16 17 18 19 15 14 13 12, Figs. 2 and 3, are without strain in two cases—to wit, when the spans are unloaded and when they are uniformly loaded. Initial strains may, 80 however, be introduced in these members, if found desirable, by raising or lowering the ends of the trusses at 1 and 5. This it will be advisable to do for very large bridges, in order to reduce the deflection of the points of 85 contraflexure, which would otherwise be considerable. Where the spans are not as described above, for which there is a complete balancing of the vertical forces at the points of contraflexure around the pier-supports, the 90 chords will be strained for the two cases mentioned. Where the end span is not of such length and weight as to resist by its own inertia the upward force at 1 due to the maximum load applied at 9, as indicated by the 95 arrows, Fig. 4, the end 1 and, correspondingly, the opposite end, 5, are to be anchored to the masonry by means of vertical anchor-bars 25 26, so arranged as to permit longitudinal expansion and contraction of the superstructure 100 from temperature without impediment, while preventing vertical movement. This may be effected in any suitable manner, as by causing the anchor-bars to bear against sliding plates or rollers placed on top of the lower 105 chords at these points. Where three spans only are used, as in Fig. 5, the chord members described may be dispensed with, as stability is attained without them, and it may, further, be found advantageous to depart from the construction of end spans shown in Figs. 2 and 3, 110 eliminating the curved members and substituting a straight-line truss or other form, as shown in Fig. 5, continuous with the middle span and anchored, as before specified. 115

Fig. 6 illustrates a construction in which, in addition to the modification of the end-span trusses by dispensing with arch members therein, the upper chord members are wholly omitted. The strains allotted to said members are 120 in this case taken by the curved members and pass through the points of contraflexure. The construction shown is specially adaptable to highway-bridges, both on account of the more graceful appearance of the structure and for 125 the reason that the strains to be taken by the chords are light, as the moving loads are seldom very unequally distributed.

Various structural modifications, which will be apparent to the skilled engineer, may be 130 made, as necessary or desirable in special cases, without departing from the principle of my invention, as hereinbefore described, and I have shown in Fig. 7, representing a

combined deck and through bridge, the facility with which my improvements may be adapted to different conditions of span lengths and position of grade on bridge.

5 Among the advantages afforded by the employment of my invention are the following:

First. The bridge can be erected either entirely or partially without false works, at low cost, with minimum of risk, and without obstructing the channel to passing vessels. The structure shown in Fig. 2 would be put in place by first erecting the two end or shore spans (which are usually at a comparatively low level above ground) upon false works, then putting up posts over the piers and holding them by guy-lines, then erecting the catenary members in the manner of the cables in suspension-bridges, by first stretching a wire rope across the stream or chasm and following up 20 with the heavier material. After the catenary is in place the other members of the truss can be readily put up by means of a traveler, the catenary forming the support for this work. It will be seen that by this mode of erection 25 no additional material is required for erection strains, as is the case in the ordinary cantilever bridge.

Second. In constructions under my improvement no ambiguity or uncertainty exists as to 30 the strains, as in cantilever bridges of the usual type, where more than one system of web-bracing is employed, and as is the case in the different forms of suspension-bridges heretofore constructed.

35 Third. Notemperature strains are to be provided for, as in elastic arch and suspension bridges, and by the elimination of said strains an important economy of material in the superstructure is effected over ordinary arch and 40 suspension bridges, as well as a still greater economy in masonry and foundations, inasmuch as vertical pressures only are sustained by the masonry.

Fourth. A material saving is effected as 45 compared with the ordinary cantilever-truss, not only because the curved members are favorable for economy, but also by the more favorable position of the points of contraflexure, which can be located nearer to the supports than in the cantilever-truss, in which 50 regard for erection strains does not permit the central portion between the points of contraflexure to be made of any considerable length.

55 Fifth. As compared with the lenticular or "Pauli" truss of equal span length, my improved truss affords twice the effective depth without greater weight of web-bracing, and the saving on this account more than balances 60 the cost of extra material required for the chord members, which are not employed in the Pauli truss.

Sixth. The appearance of a bridge constructed with my improved trusses is light and graceful.

I am aware that the combination of a catenary and an arch intersecting in the manner

hereinbefore described has been heretofore proposed in bridge-trusses, but in such case the means adopted to obtain stability against 70 forces induced by the loading of one span singly (to prevent canting over of pier-posts) was to build the piers *encastré* with the superstructure—that is to say, to unite them with the superstructure to a solidarity, causing 75 them to resist said forces by their transverse or bending strength. I therefore disclaim the combination, *per se*, of said curved members.

I claim herein as my invention—

1. In a truss or girder for an intermediate 80 span of a bridge consisting of three or more continuous spans, the combination, substantially as set forth, of a downwardly-curved member and an upwardly-curved member intersecting in two points of contraflexure between pier-supports, and a straight chord member connecting said pier-supports, the curved members being connected by a system of web-bracing with each other, but not with the straight chord member. 85

2. In a truss-bridge having three or more continuous spans, the combination, substantially as set forth, of an intermediate -span truss having a downwardly-curved member and an upwardly-curved member intersecting 95 in two points of contraflexure between pier-supports, and a straight chord member connecting said supports one with the other and with the ends of the bridge, said curved members in the intermediate-span truss being connected by a system of web-bracing with each other, but not with the straight chord members. 100

3. In a truss-bridge having three or more continuous spans, the combination, substantially as set forth, of an intermediate -span truss having a downwardly-curved member and an upwardly-curved member intersecting 105 in two points of contraflexure between pier-supports, and connected by a system of web-bracing, an end-span truss, and a vertical anchor-bar secured to a foundation and bearing at top on said end-span truss in such manner as to allow of a sliding or rolling longitudinal motion of said span, thereby permitting 115 longitudinal expansion and contraction of the structure, while preventing vertical movement thereof. 110

4. In a truss-bridge having three or more continuous spans, the combination, substantially as set forth, of an intermediate -span truss having a downwardly-curved member and an upwardly-curved member intersecting 120 in two points of contraflexure between pier-supports, a straight chord member connecting 125 said pier-supports, and an end-span truss having a downwardly -curved member and a straight chord member, which are connected one to the other at the outer end of the end span. 130

5. In a truss-bridge having three spans, the combination, substantially as set forth, of a middle-span truss composed of a downwardly-curved member and an upwardly-curved mem-

ber intersecting in two points of contraflexure between pier-supports, and two end-span trusses continuous with said center-span truss.

6. In a truss-bridge having three or more spans, the combination, substantially as set forth, of one or more intermediate-span trusses, each having a downwardly-curved member and an upwardly-curved member intersecting in two points of contraflexure between pier-supports, upper and lower straight chord members connecting said pier-supports

above and below the trusses, and chord members connecting the outer end supports adjacent to the end spans with the ends of the bridge.

In testimony whereof I have hereunto set my hand.

CHARLES L. STROBEL.
